UNITED STATES PATENT OFFICE.

FRANK THEODORE WILLIAMS, OF MERIDEN, CONNECTICUT, ASSIGNOR TO
THE EDWARD MILLER & COMPANY, OF SAME PLACE.

DESIGN FOR A LANTERN.

SPECIFICATION forming part of Design No. 27,717, dated October 12, 1897.

Application filed August 18, 1897. Serial No. 648,724. Term of patent 7 years.

To all whom it may concern:

Be it known that I, FRANK THEODORE WILLIAMS, a citizen of the United States, residing at Meriden, New Haven county, Connecticut, cut, have invented certain new and useful Improvements in a Design for a Lantern, of which the following is a full, clear, and exact description.

My design is illustrated by the accompanying drawings, in which—

Figure 1 is a plan view. Fig. 2 is a side elevation. Fig. 3 is a view of the bottom and under side of the base of the lamp.

The leading features of my design are the general outline and ornamentation as herein set forth.

A is the body of a lamp, the upper edge of which curves outwardly to form an overhanging flange, merging gracefully into the head portion or crown. Around the head portion are a plurality of ornamental beads B B, spaced apart from each other, between which are a series of elongated horizontally-arranged ornamental openings C C. The upper surface or extreme top of the lamp is provided with a system of concentric rings D D, arranged in terraces converging toward the center. Around the body A of the lamp and below the head portion is a circumferential band of small vertically-arranged ornamental openings E.

F is a front reflector having diverging or flaring sides and a horizontal median line with respect to the body portion A, from one side of which the said reflector projects. 35

G is an enlarged base the sides of which are convexed throughout.

H H are small horizontally-arranged openings between the body A and the base G.

I is an annular bead midway in the base 40 G and extending around said base at its greatest diameter.

J is an annular bead at the lowermost part of the base G, concentric with the bead I and of slightly-smaller diameter. Between the 45 beads I and J is provided a conspicuous series of upright shell-like beads or ornamentations K, radially arranged when viewed from the under side of the lamp, as shown in Fig. 3. The surface within the bead I is knurled or 50 roughened, so as to be useful as a place to scratch matches as well as to give an ornamental effect thereto.

What I claim is—

The design for a lantern as herein shown 55 and described.

FRANK THEODORE WILLIAMS.
